United States Patent Office

ELI SWEET, OF WHITNEY'S POINT, NEW YORK.

Letters Patent No. 63,332, dated March 26, 1867.

IMPROVEMENT IN HAY LOADERS.

The Schedule referred to in these Letters Patent and making part of the same.

TO ALL WHOM IT MAY CONCERN:

Be it known that I, ELI SWEET, of Whitney's Point, in the county of Broome, and State of New York, have invented a new and useful Improvement in Hay-Loading Wagon; and I do hereby declare that the following is a full, clear, and exact description thereof, which will enable others skilled in the art to make and use the same, reference being had to the accompanying drawings, forming part of this specification, in which—

Figure 1 is a central vertical longitudinal section of my improved hay-loading wagon.

Figure 2 is a detached bottom view of the front part of the running gear.

Similar letters of reference indicate like parts.

This invention relates to new and improved devices attached to wagons for loading hay or fodder in the field or barn, and consists in the combination of a crane and single-pulley rope with a pitch-fork and a sliding tongue, in connection with a brake on the fore wheels, in such manner that by the sliding of the tongue when it is tripped the horses hoist the fork with the hay, and at the same time chock the wagon by the action of the brake, the whole draught being very light, and the operation convenient.

A represents an ordinary farm-wagon body, to which my improved hay-loading devices may be attached temporarily for use. B is the crane post, and C the jib of a crane set near the middle of the wagon, provided with pulleys as usual for the rope a, on one end of which is the hay fork D, and passing from the fork over the jib of the crane, and down the post in a groove on the side to and through a hollow part in the lower end of the post over a small pulley, b, at the foot, and thence to and around a larger pulley, c, attached to the under side of the rear end of a sliding tongue, E, which tongue is connected with the lower side of the draught-pole F, as usual. Provision is made for locking the sliding tongue to the stationary pole when set back by means of a latch pin, d, on a pivoted lever, d', connected by the cord d'' with the head of the front wagon standard e, where it is managed as usual by the driver, who stands on the front part of the wagon to assist in loading. The rope a passes from the pulley c to the middle of a brake-bar, g, where the other end of the pulley rope is fastened. The brake-bar g is held in slides, h h, on the under side of the hounds k, and is provided with shoes as usual to bear against the fore wheels G.

The operation of these devices for loading hay on the wagon is very simple and easy. The wagon runs along the row of hay-cocks or down the side of a windrow to sweep the hay with a broad-tined fork till it gets full, and in either case when the fork is loaded the pin d is tripped by the driver by lifting the lever d' with the cord d'', when the horses draw forward the sliding tongue E, to which they are attached, when the draught comes upon the pulley rope a, and instantly acts upon the brake-bar g to stop the wagon; at the same moment the draught comes on the loaded hay fork D attached to the other end of the pulley rope a, and hoists the fork with its load up on the wagon to be deposited at any part desired by the loader, who merely directs and regulates the movement of the loaded fork by means of the crane, as will be readily understood. When the fork drops its load the horses are backed, and the operation of loading is continued in the same place, or the pin d is dropped to lock the tongue and move on with the wagon to another place for loading. By my arrangement of small pulleys close up under the wagon for operating the fork and brake together with a single-pulley rope, it will be seen that there is nothing in the way to catch upon stumps in a field; that the draught is very easy and light, requiring only a single five-eighths or three-quarters of an inch rope to do the work of both elevating the fork and operating the brakes together, since all the weight on the fork falls on the brake, and no extra power is applied to the brake. The arrangement of the pulleys also gives an extension of the rope over the jib of the crane to the fork more than four times the distance moved by the sliding tongue, so that by moving the tongue four feet the fork has over sixteen feet play of rope to load with, which is ample.

Having described my invention, I do not claim operating a hay fork by means of a rope connected to the sliding tongue as described in the patent of A. McClara, August 28, 1866, but what I claim is—

The arrangement of the sheave in the sliding tongue, and moving therewith the rope passing over the said sheave and connected at its respective ends to the fork and to the brake-bar on the tongue hounds.

The above specification of my invention signed by me this 6th day of February, 1867.
